TELEPHONE EARRING GUARD ATTACHMENT OR SIMILAR ARTICLE

Donald C. Porter, Portland, Oreg.

Application July 16, 1957, Serial No. 46,959

Term of patent 14 years

(Cl. D26—14)

Figure 1 is a front elevational view of a telephone earring guard attachment or similar article, showing my new design; Figure 2 is a rear elevational view; Figure 3 is a side elevational view, the opposite side having substantially the same appearance; Figure 4 is a top plan view; and Figure 5 is a cross-sectional view thereof taken on line 5—5 in Figure 1. The broken line showing of a telephone receiver in Figure 5 is for illustrative purposes only.

I claim:

The ornamental design for a telephone earring guard attachment or similar article, substantially as shown and described.
